UNITED STATES PATENT OFFICE.

SETH WARNER HOAG, OF GRAND ISLE, VERMONT.

MATCH-BOX.

SPECIFICATION forming part of Letters Patent No. 311,129, dated January 20, 1885.

Application filed February 29, 1884. (Model.)

To all whom it may concern:

Be it known that I, SETH WARNER HOAG, a citizen of the United States, residing at Grand Isle, in the county of Grand Isle and State of Vermont, have invented a new and useful Match-Box, of which the following is a specification, reference being had to the accompanying drawings.

My invention relates to match-boxes; and it has for its object to provide a device of this character whereby a card or strip of wood previously dipped in a combustible composition is automatically cut to the proper size, lighted, and then placed within easy access of the user.

A further object of the invention is to provide improved means for automatically feeding the card of matches to the cutter.

A further object of the invention is to provide improved means for automatically returning the cutter to its normal position.

A further object of the invention is to provide improved means for automatically lighting the matches, thus obviating the liability of a person to scratch matches upon the furniture or walls through carelessness or otherwise.

A still further object of the invention is to provide a device of this character which shall be simple in its construction and effective and durable in use.

With these ends in view the invention consists in the combination, with a suitable box, of a platform or tray for holding a card of matches, and means for automatically feeding the same to the cutter.

The invention further consists in the combination, with a suitable box or casing, of a sliding cutter, and means for automatically feeding the card of matches to the same.

The invention further consists in the combination, with a suitable box or casing, of a sliding cutter, and means for automatically returning the same to its normal position after a match has been cut.

The invention further consists in the combination, with a suitable box or casing, of a sliding cutter, and a suitably-arranged serrated plate, whereby the matches are automatically ignited.

The invention further consists in the combination, with a suitable box or casing, of a

sliding cutter, a serrated plate for igniting the matches, and a platform or tray for holding the matches after ignition.

The invention further consists in the details of construction and combinations of parts, hereinafter fully described, and pointed out in the claims.

In the drawings, Figure 1 is a perspective view of a match-box constructed in accordance with my invention, with the cover removed. Fig. 2 is a transverse vertical section of the same on the line $x-x$ of Fig. 4. Fig. 3 is a detached plan view of the sliding cutter. Fig. 4 is a transverse section on the line $y-y$ of Fig. 2, and Fig. 5 is a detached view in perspective of the feeding-roller.

In the accompanying drawings, in which like letters refer to corresponding parts throughout the several figures, A represents a box or casing, which is made of cast metal, though wood or other material may be used in the construction of the same. Upon the rear of this box or casing A, and in the sides thereof, are formed grooves, in which slides the cutter B. This cutter B is provided on its inner side, and near the top of the same, with a projecting portion, a , which is formed with a recess, a' , and an opening upon its side, a'' . The recess in this projecting portion a is adapted to receive the end of a coil-spring, C, the other end of which is secured in a projecting lug, c , formed in one corner of the box, near the front end thereof. This spring is for the purpose of returning the cutter to its normal position after it has been depressed to cut and ignite a match.

Upon the inner side of the sliding plate B, and near the edges thereof, are provided brackets or stop-lugs D, which engage with outwardly-projecting lugs D', formed upon the inner sides of the box, and thus limit the vertical movement of the sliding cutter further than to allow of its proper working.

E represents a strip of spring metal, which is secured at its upper end to the inner side of the sliding cutter B, and having its lower end bent outwardly to form a hook portion, e' , for a purpose to be explained.

Upon the lower inner corners of the sliding cutter B are provided outwardly-projecting brackets e , which are recessed or cut away at about the center of their length, forming a

seat, *f*, which, when the matches are cut, carries them to the bottom of the box or casing within easy reach of the user.

F represents a platform, upon which is placed the card or strip of matches to be cut. The rear upper edge of this platform is provided with a cutting-edge, *g*, and a downwardly-projecting strip, *g'*.

G represents a feed-roller, which is mounted in the sides of the box, and which is provided with rubber disks *H*, near the ends of the same. Upon the center of this roller *G* is provided a milled disk, *I*, which, when the cutter is depressed, is engaged by the strip of spring metal, *E*, which partially rotates the same far enough to feed the card of matches automatically forward the width or thickness of an ordinary match.

J represents a serrated spring, which is secured to the inner side of the box or casing *A* just below the point occupied by the brackets *e* when the device is in its normal or raised position, so that when the cutter is depressed the end of the match will project from the side of the seat *f*, and will be ignited by contact with said plate.

K represents prongs or arms, which receive the match after it has been released from the seat *f*, and which are secured to the bottom or floor of the casing or box *A*.

L represents a tray for containing a supply of the card matches, which is secured in grooves in the inner sides of the box or casing *A*, just above the platform *F*.

The operation is as follows: A strip or card of matches is placed upon the platform, with a sufficient portion of the same under the roller to insure it being properly fed forward. The top of the cutter is then forced down by a quick blow, which cuts a match and carries it in the seat *f* to the serrated plate, with which it is brought in contact, thus igniting the same. The match, as soon as it passes the platform, when the sliding cutter is depressed, drops from said seat and falls upon the upwardly-projecting prongs or arms, from which it may be taken for use, the sliding cutter being returned to position by means of the coil-spring before described.

It will be readily seen from the above description that by the use of my invention the matches are cut, ignited, and thrown within easy reach of the user. It will also be seen that its operation is simple and effective.

It will also be obvious that many slight changes in the details of construction may be resorted to without departing from the spirit of my invention; hence I would have it understood that I do not limit myself to the precise construction shown and described, but reserve to myself the right to make all such slight changes and alterations as may properly fall within the scope of my invention.

Having fully described my invention, what I claim as new, and desire to secure by Letters Patent, is—

1. In a match-box for automatically lighting matches, the combination, with a suitable box or casing, of a platform or tray for holding the matches, a sliding cutter, and means for automatically feeding the matches thereto, substantially as set forth. 70

2. In a box for automatically lighting matches, the combination, with a suitable box or casing, of a sliding cutter, a tray for holding the matches, means for automatically feeding the matches to said cutter, and a lighting device, substantially as set forth. 75

3. In a box for automatically lighting matches, the combination, with a suitable box or casing, of a sliding cutter and a lighting device, and means for automatically returning the same to its normal position after a match has been cut, substantially as set forth. 80

4. In a box for automatically lighting matches, the combination, with a suitable box or casing, of a sliding cutter and suitably-arranged serrated plate, substantially as set forth. 85

5. In a box for automatically lighting matches, the combination, with a suitable box or casing, of a sliding cutter provided on its inner side with outwardly-projecting lugs, and lugs projecting outwardly from the inner sides of said box or casing, substantially as set forth. 90

6. In a box for automatically lighting matches, the combination, with a suitable box or casing, of a sliding cutter, a serrated plate for igniting the matches, and upwardly-projecting arms to receive the same after ignition, substantially as set forth. 100

7. In a box for automatically lighting matches, the combination, with a suitable box or casing, of a cutter sliding in guides formed on the rear side thereof, a coil-spring secured to the upper end of said cutter, its other end being secured to the inner side of the casing, and lugs formed upon the inner side of the casing adapted to engage lugs projecting outwardly from the sliding cutter, substantially as set forth. 105

8. In a match-box for automatically lighting matches, the combination, with a sliding cutter, of a platform or tray for holding a card of matches, and roller for feeding the same to the cutter, substantially as set forth. 115

9. In a match-box for automatically lighting matches, the combination, with a sliding cutter, of a platform for holding a card of matches, and a roller mounted in the sides of the box, said roller being provided with rubber disks, whereby the matches are automatically fed to the cutter at each downward stroke of the same, substantially as set forth. 120

10. In a match-box for automatically lighting matches, the combination, with a sliding cutter having a strip of spring metal secured to its inner side, the lower or free end of which is bent outwardly, of a platform for holding the matches, and a roller having bearings in the sides of the casing, said roller hav- 125
130

ing a serrated disk to engage the end of the said spring, substantially as set forth.

11. In a match-box for automatically lighting matches, the combination of a sliding cutter having a strip of spring metal secured at its upper end to the inner side thereof, the lower or free end being bent outwardly, said cutter being also provided with brackets at its lower ends, which are provided with transverse slots, and a roller, substantially as set forth.

12. In a match-box for automatically lighting matches, the combination, with a sliding cutter provided at its lower corners with brackets having transverse slots, of a platform having a downwardly-projecting strip, whereby a match is held in said slots until the lower end of the said strip has been reached, substantially as set forth.

13. In a match-box for automatically lighting matches, the combination, with a sliding cutter having a strip of spring metal secured at its upper end to the inner side thereof, the lower or free end being bent outwardly, said cutter being also provided at its lower corners with brackets having transverse slots, of a platform having a downwardly-projecting strip at its front end, and a roller provided at about its center with a serrated disk, substantially as set forth.

14. In a match-box for automatically lighting matches, the combination, with a sliding cutter having a strip of spring metal secured at its upper end to the inner side thereof, the lower or free end being bent outwardly, said

cutter being also provided at its lower corners with brackets having transverse slots, of a platform having a downwardly-projecting strip at its front end, a roller provided at about its center with a serrated disk, and a serrated plate secured to the inner side of the casing just below said platform, substantially as set forth.

15. In a match-box for automatically lighting matches, the combination, with a sliding cutter having a strip of spring metal secured at its upper end to the inner side thereof, the lower or free end being bent outwardly, said cutter being also provided at its lower corners with brackets having transverse slots, of a platform having a downwardly-projecting strip at its front end, a roller having a centrally-located serrated disk, a serrated plate secured to the inner side of the casing, and arms projecting upwardly from the floor thereof, substantially as set forth.

16. In a match-box for automatically lighting matches, the combination, with a suitable box or casing, of a sliding cutter, a feed-roller, and a spring for actuating said feed-roller at each downward stroke of the cutter, substantially as set forth.

In testimony that I claim the foregoing as my own I have hereto affixed my signature in presence of two witnesses.

SETH WARNER HOAG.
